UNITED STATES PATENT OFFICE

NILE OLDHAM, OF CHICAGO, ILLINOIS

ROLL-SCREEN CONSTRUCTION

Application filed April 8, 1927. Serial No. 181,909.

This invention relates to a new and improved roll screen construction and more particularly to an improved track and bottom rail construction for such screens. Screens which roll up on rollers have heretofore been manufactured with bottom rails fixedly secured thereto, the rails having rigidly connected end portions which ride on the side guides or tracks. The rigid bottom rail construction has required that the tracks be accurately spaced and be absolutely parallel with each other so that the screen may move up and down without binding. It has also been customary to spot-weld or solder the screen to the roller and to the bottom rail. This practice requires considerable high priced labor as well as expensive machinery and adds materially to the cost of the finished product. Another drawback of such construction lies in the large expense involved to replace a torn or damaged screen since substantially the entire structure must be replaced.

It is an object of the present invention to provide a screen construction in which the guiding portions of the bottom rail are yieldingly connected to the screen whereby binding in the guides is eliminated.

It is a further object to provide a construction having a simple and substantially rigid form of side rail or track.

It is also an object to provide a construction in which the screen is firmly but detachably secured to the roller and to the bottom rail.

Other and further objects will appear as the description proceeds.

I have illustrated in the accompanying drawings a preferred embodiment of my invention.

In the drawings—

Figure 1 is a fragmentary view partly in section showing the entire screen construction;

Figure 2 is a section taken on line 2—2 of Figure 1;

Figure 3 is a section taken on line 6—6 of Figure 1; and

Figure 4 is a perspective view of a bottom rail guide member.

The screen is carried in a housing 11 which is secured to a window frame 12 by means of the angle members 13 and 14, which latter are connected by bolts 15 to the end caps 16 of the housing. The housing contains the outwardly facing supporting caps 17 in which is journaled the shaft 18. One end of the shaft is split, as shown at 19, and the pin 21 is inserted in this split. This pin 20 prevents rotation of the shaft 18. The opposite end of the shaft carries the cotter pin 21 which serves to limit endwise movement of the shaft.

The hollow roller 22 is rotatably supported upon the shaft 18 by the end members 23 and 24. The spring 25 has one end 26 secured to the shaft 18 and the other end 27 secured to the hollow roller 22. The roller 22 is provided with a longitudinally extending recess 28 which is substantially circular in cross section. The recess 28 opens through the side of the roller 22 with a narrow slot. The end of the screen 29 extends down into the slot 28 and around a retaining member 30 and out of the slot upon the opposite side.

The guide members 31 are secured by bolts 32 to the angle supporting members 33. The angles 33 are secured to the window frame by screws 34, as best shown in Figures 2 and 5. The guides or track members are formed of a single piece of sheet metal which is bent upon itself to form a substantially cylindrical cavity 35. This cavity is provided with double walls which afford a very rigid construction, although made of relatively light gauge material. One edge 36 of the guide is bent around the opposite edge 37 which also serves to strengthen the construction as well as give it a smooth finish. The rails are preferably provided with a pair of bolt holes 38 for each bolt so that the track may be secured to the supporting angle in either of two selected positions.

The bottom rail 39 also consists of a single strip of sheet metal bent upon itself to the desired form. The strip may be said to have one edge at point 40 and at the upper point 41, is bent horizontally and then down to form the substantially cylindrical portion 42, up again to the point 43, then down to

the point 44 and out and back to form the double thickness extension 45. The lower bend extends over to have its edge abut against the other edge at 40. The lower end 5 of the screen extends down between the spaced portions of the bottom rail into the cylindrical chamber 42 and around the retaining member 46 and up a short distance parallel to the downwardly extending portion. The cut edge of the screen is thus 10 housed within the bottom rail.

The end clips 47 are shown in perspective in Figure 4 and the two parallel legs 48 are shown in section in Figure 3. These legs are 15 provided with outwardly bent portions 49 which fit about the cylindrical portion 42 of the bottom rail. The legs 48 bend inwardly closely adjacent each other at 50 and are then bent out to form the integral substantially tubular portion 51. The bottom portion 20 of the legs 48 is cut away so as to form notches 52 which are equal in depth to the thickness of the material. This enables the bottom of the neck portion 50 and tubular portion 51 to fit down flush with the bottom 25 face of the rail 39.

The edges of the screen travel in the tubular chambers in the guides or rails 31 and the screen edges may have staples 53 secured 30 thereto so as to prevent the edges from pulling out of the rails. The rails shown are quite rigid and will not spring apart to permit the staples to pull out under any normal pressure. However, the upper outer portion 35 of each rail is preferably cut away diagonally as shown at 54, so as to permit the reinsertion of the staples into the rail guideway should any be pulled out. The back half of the rail 31 extends up flush with the bottom 40 of the housing 11, as best shown in Figure 1.

Any suitable clip may be provided to engage the bottom rail to hold the rail down against the tension of the spring 25 which tends to raise the screen. This tension is 45 largely counteracted, however, by the frictional engagement of the tubular portions 51 with the guide members 48 within the guide rails. The guide members 48 are formed of 50 spring metal and have a definite resilient engagement with the guide members.

In assembling the screen to the roller and also to the bottom rail, the retaining members 30 or 46 are placed transversely of the screen adjacent the end thereof and the screen 55 is folded about them. These members need not be rigid metal members but a flexible cord has been found to serve satisfactorily for this purpose. If desired this cord may be saturated with a lubricant to prevent rust. It has 60 also been found that once the screen has taken the form shown, the cord or other member may be removed and the screen itself has sufficient rigidity to be retained firmly in engagement with the roller or bottom rail. It will 65 be understood that after the screen is given

this formation, it is assembled with the bottom rail or roller by sliding the engaging portion of the screen endwise into the groove formed in the member. It will be seen that this method of assembly is much cheaper 70 than spot-welding or soldering, as has been done heretofore, and also permits of ready separation of the parts. A damaged screen may be readily removed and a new one replaced without the use of tools or destroying 75 any other portions of the assembly. If the screen has been torn or injured adjacent its ends, merely a small portion can be cut off and the new end of the screen readily formed to fit with the groove. 80

The guide members 48 are merely frictionally held within the ends of the bottom rail 39 proper. They may move in and out of the rail as required by any lack of parallelism between the tracks. This makes a careful 85 and exact adjustment of the tracks unnecessary and greatly facilitates installation of the construction. It will be noted that the portions 49 of the guide members closely grip the portions 42 of the rail 39 and the tops and bottoms of the members 48 also closely fit 90 within the rail so that these guide members, while they may slide either in or out, cannot tilt or get into angular relation with the rail.

It will be apparent that my construction 95 consists of a plurality of parts all of which may be assembled without any soldering or spot-welding operation, thus minimizing labor and machine expenses. The parts may also be readily separated for repair and renewal which is a large factor in reducing 100 upkeep costs.

While I have shown certain preferred 105 forms of construction by way of illustration, I contemplate such changes and modifications as come within the spirit and scope of the appended claims.

I claim:

1. In a roll screen construction, having a screen, a bottom rail secured to the screen, 110 and guide members comprising reversely and guide members comprising reversely bent resilient metal elements having legs fitting within the bottom rail and an intermediate portion adapted to engage a side track. 115

2. In a screen construction, an integral transverse sheet metal member having portions forming a longitudinal groove, the open side of the groove being narrower than a lower portion of the groove, said portions adapted to grip a screen secured to said member by having a reversely bent portion of the screen extending within the lower portion of the groove, said member having other portions forming a hollow body member open at the ends. 120

3. In a screen construction, a metal bottom rail formed of sheet metal bent upon itself to form a narrow longitudinal slot, the ends of the rail being open, and guide mem- 125

bers having portions adapted to fit into the ends of the rail between the outer rail portions and the portions bent inwardly to form the slot.

5 4. In a screen construction, a metal bottom rail formed of sheet metal bent upon itself to form a narrow longitudinal slot, the inner portion of the slot being substantially circular in cross section, the ends of the
10 rail being open, and guide members having portions adapted to fit into the ends of the rail between the outer rail portions and the portions bent inwardly to form the slot, said guide members having portions curved to
15 fit the substantially circular portion of the slot forming part of the rail member.

5. In a screen construction, a transverse bar member of sheet metal, said sheet metal bent upon itself to form a hollow body portion open at the ends and adapted for the insertion of guiding members, a finger grip extension from said body portion whereby said bar member may be moved, and a longitudinal open sided groove for the attachment of screen cloth, said groove being restricted adjacent the entrance thereof.

Signed at Chicago, Illinois, this 2nd day of April, 1927.
